(57) **CLAIM**

The ornamental design for amplifier case, as shown and described.

DESCRIPTION

FIG. 1 is a top, front, and right side isometric view of an amplifier case showing my design.

FIG. 2 is a top view thereof.

FIG. 3 is a bottom view thereof.

FIG. 4 is a front elevation view thereof.

FIG. 5 is a rear elevation view thereof.

FIG. 6 is a left side elevation view thereof; and,

FIG. 7 is a right side elevation view thereof.

The broken lines represent the portions of the design that form no part of the claim.

1 Claim, 4 Drawing Sheets
